Attorney

UNITED STATES PATENT OFFICE

GEORGE PADIS, OF NORFOLK, VIRGINIA

MARINE PROPELLER HAVING A TRANSVERSE MOTION

Application filed December 24, 1931. Serial No. 583,098.

This invention appertains to marine propulsion and more particularly to a novel device for propelling boats, wherein the motive means is employed substantially at the point 5 of application of use.

One of the primary objects of my invention is the provision of novel means for propelling boats, embodying a propeller of a 10 novel shape which operates with transverse movement across the longitudinal axis of the boat in lieu of the usual screw propeller now generally employed in marine propulsion, the novel propeller acting to steady the vessel and to prevent sidewise swaying of the 15 vessel now apparent in vessels using screw propellers.

A further object of my invention is the provision of novel means for operating the propeller, whereby the same can be actuated 20 on the lever principle and whereby the motive fluid utilized for operating the propeller can be employed substantially at the point 25 of operation of the propeller, thereby avoiding all loss of power and the like.

A further salient object of my invention is the provision of a novel means for propelling a boat, embodying a spoon shaped propeller, with means for swinging the propeller 30 transversely of the boat, said means embodying a novel piston blade arranged on the opposite side of the axis from the propeller and disposed within a V-shaped cylinder, with 35 novel means for controlling the flow of the steam or other operating fluid from and to the cylinder on opposite sides of the piston blade.

A still further object of my invention is to provide an improved device of the above 40 character which will be durable, and efficient in use, one that will be simple and easy to manufacture and one which can be placed upon the market and incorporated with a vessel at a low cost.

With these and other objects in view, the 45 invention consists in the novel construction, arrangement and formation of parts, as will be hereinafter more specifically described, claimed and illustrated in the accompanying drawing; in which

50 Figure 1 is a side elevation of a boat

equipped with my improved propelling device, parts of the boat being shown broken away to illustrate the application of my device:

Figure 2 is a rear elevation of my improved 55 device with parts thereof broken away and in section to illustrate the novel construction thereof;

Figure 3 is a side elevation of my improved 60 boat propelling device, looking from the opposite side from that shown in Figure 1;

Figure 4 is a top plan view of my improved 65 device illustrating the means employed for actuating the slide valve in the steam chest;

Figure 5 is a horizontal section taken on the line 5—5 of Figure 2, looking in the direction of the arrows illustrating the novel formation of the cylinder and the means for controlling the flow of steam to and from 70 the opposite sides of the cylinder;

Figure 6 is a vertical section taken on the line 6—6 of Figure 2, looking in the direction of the arrows, illustrating the construction of the power cylinder and piston blade; 75

Figure 7 is a detail perspective view of the slide valve for controlling the exhaust and inlet ports of the steam;

Figure 8 is a fragmentary detailed side elevation illustrating a slightly modified form 80 of connecting the propeller with the power shaft.

Referring to the drawing in detail, wherein similar reference characters designate corresponding parts throughout the several views, the letter "A" generally indicates my improved device and "B" a boat with which the same can be associated.

The boat "B" forms no part of the present 90 invention and will not be described in detail, but it is to be noted that my improved propelling device "A" is mounted in the stern thereof.

My improved device "A" comprises an 95 upright casing 10 arranged transversely of the boat "B", which casing is provided with diverging partition walls 11 and 12 defining a closed V-shaped power cylinder 13. The partition walls 11 and 12 extend entirely 100

across the upright casing 10 to form the closed cylinder.

The cylinder on opposite sides of its vertical axis is provided with ports 14 and 15, which lead to a steam chest 16 carried by one face of the upright casing. An exhaust passage 17 is provided in one wall of the steam chest and the chest receives a hollow slide valve 18.

10 Mounted for oscillating movement within the cylinder 13 is a piston blade 19 and this blade is secured to or forms a part of the power shaft 20, mounted at the bottom of the cylinder. The power shaft 20 is horizontally disposed and extends longitudinally of the vessel and can be mounted in suitable bearings 21. Particular attention is invited to Figure 6 of the drawing and it will be noted that the bottom of the cylinder is provided 15 with a substantially circular bearing way for receiving the shaft 20 which precludes the seeping of water into the cylinder, it being understood that the normal steam pressure in the cylinder will likewise tend to act as 20 a packing around the shaft to prevent the entrance of water in the cylinder.

From the description so far, and by referring to Figure 4, it will be noted that when the slide valve 18 is in the position, shown in 30 said figure, steam is permitted to enter the steam chest 16 from the steam inlet pipe 22, and the same will flow into cylinder 13 through the port 14 consequently moving the piston blade 19 to the left. Exhaust steam 35 will then flow through the port 15 into the hollow slide valve 18 and out of the exhaust passage 17. Upon reverse movement of the slide valve 18, the same will cover the channel leading to the port 14 and open the channel leading from the port 15, consequently, the steam will flow above and below the slide valve and into the port 15 for moving the piston blade 19 to the right.

The exhaust steam will then flow through 45 the port 14 into the hollow slide valve and out of the exhaust passageway 17. This operation is continued as long as steam is permitted to flow into the steam chest and the steam can be derived from any suitable 50 boiler or other steam generating device.

In order to properly actuate the slide valve 18 in proper timed relation, the power shaft 20 is provided with a crank arm 23 having connected thereto, a pitman 25, which is operatively connected to one end of a double lever 26. This double lever is rockably mounted as at 27 on a suitable upright standard 28. The opposite end of the lever has operatively connected thereto, a link 29 which is connected to the slide valve 18. A suitable stuffing box can be employed around the link 29 to prevent leakage of the steam.

Formed on or secured to the shaft 20 in any desired way is my depending propeller 60 30, which forms an important part of the

present invention. As shown, this propeller is of a spoon shape and gradually tapers toward its lower end and is dished to provide a substantially concavo-convex body, with the concaved portion disposed rearwardly. 70

In the preferred form, I have shown the propeller arranged directly below the piston blade 19, but it is to be understood that the propellers can be arranged on opposite sides 75 of the blade as indicated by the reference character 31 in Figure 8 of the drawing. In this instance, the bottom of the cylinder can be completely closed by a removable plate 32.

Obviously, from the foregoing description, 80 the propeller will be oscillated transversely of the vessel, causing a continued pressure on the water acting to propel the boat forward.

From the foregoing description, it can be seen that my invention has for its principal 85 advantages the simplicity of mechanical functions and a movement whereby propulsion is induced to a greater range, since the spoon traverses in an arc about 90°.

The construction of the spoon creates at 90 each stroke two channels of propulsion which indicates that my device replaces the costly arrangement of two screw propellers. Since a vessel has a natural tendency to sway, 95 that is, from port to star-board and vice versa, this movement which traverses and operates in a similar way would counteract this swaying motion and add stability to the ship.

My device provides direct power to the 100 point of resistance, which eliminates a number of parts and complications now inherent in all screw steamers, thus making the construction of this invention possible at a nominal cost. Its feature of simplicity commands to 105 its side the great feature of economy, first the economy in construction, second, economy in consumption of power, third, in operating cost as to fuel and operating hands, and fourth less lubrication and economy in space. 110 The smooth operation of the device decreases vibration, thereby insuring longevity to the device and the ship with which it is associated.

The bulbous shape of the spoon provides 115 at each stroke the creation of a suction at its rear, thus sucking a water stream to it and then forcing it into two channels of propulsion.

While I have specified steam for the motive fluid, it is to be understood that other power can be used.

Changes in details may be made without departing from the spirit or the scope of the invention, but what I claim as new is:

1. A propelling device for boats comprising a V-shaped cylinder, a rock shaft extending through the lower end of the cylinder and closing the same, a piston blade on the shaft received in the cylinder, means for 130

controlling inlet and outlet of fluid from the cylinder on opposite sides of the blade including a slide valve, a crank on the shaft, a double ended lever rockably mounted intermediate its ends, a pitman rod operatively connecting the crank to one end of the lever, and a link connecting the opposite end of the lever to the slide valve.

5 2. A propeller for boats comprising a concavo-convex body gradually tapering toward its opposite ends.

10 In testimony whereof, I affix my signature.
GEORGE PADIS.
